UNITED STATES PATENT OFFICE.

STEPHEN D. BAKER, OF NEW YORK, N. Y.

URINAL.

1,114,670.

Specification of Letters Patent. Patented Oct. 20, 1914.

Application filed March 25, 1913. Serial No. 756,635.

To all whom it may concern:

Be it known that I, STEPHEN D. BAKER, a citizen of the United States, residing at New York city, in the county of New York and State of New York, have invented certain new and useful Improvements in Urinals, of which the following is a specification.

Urinals of the so-called "stall" type as now commonly constructed, with a bottom, two side walls and a back, require a wasteful use of water and the necessary appurtenances for supplying it in order to flush properly the large service area which they present. They further involve the very considerable disadvantage that they have no means to confine the urine spatterings to the flushed area, in consequence of which such spatterings wet the shoes and trousers of the user and soon produce an unclean and unsanitary condition in and around the urinal. They are, moreover, extremely difficult to form because their size and the fact that they contain no inherent reinforcement make them awkward to handle without distortion before they become hardened in the kiln and give rise to warping in the baking process.

This invention consists in certain improvements in urinals of the kind indicated having for their objects to produce a urinal of this type which shall more perfectly fulfil the requirements of sanitation and cleanliness than those now in use, may be manufactured with less possibility of distortion or other blemish, and in general be more efficient and suitable for the special purpose for which such structures are intended.

In the accompanying drawings, in which the invention is fully illustrated, Figure 1 is a perspective view of the improved urinal; Fig. 2 is a substantially central vertical sectional view thereof; Fig. 3 is a plan view; and, Figs. 4 and 5 are horizontal sectional views on line $x-x$ and $y-y$ of Fig. 2.

The stall formation of the improved urinal is obtained in the preferred form of the invention illustrated by employing two vertical walls $a a$ set at an angle—preferably 90°—to each other. These walls are joined at the bottom by the horizontal wall b , and

at the top by the ledge or overhang c . They are further joined by the wall d which forms with so much of the walls $a a$ as is back of it the urinal chamber e and which extends from the ledge c to the wall b . It will be understood that these several parts form one integral structure.

The wall b forms the base of the structure and its top surface is formed with a shallow basin f whose bottom slopes at all points toward the urinal outlet g arranged at the back in such manner that the drip from the inner surface of the urinal chamber will fall directly into it, as will herein-after be more particularly explained. The wall b is adapted to be set in the floor of the apartment, as shown in Fig. 2, so that its top surface h will be flush with the floor surface.

The ledge or overhang c has its upper surface i horizontal, but its under surface j is beveled, the angle of the bevel increasing from each outer end of the ledge toward the middle thereof, the result being to improve the appearance of the whole structure, reinforce its upper part (especially against distortion either before or while undergoing the baking process) and give the necessary pitch to the bottom of a water-supply chamber k , which is formed in the said ledge, toward the discharge outlet l of said chamber; the outlet l may be a series of holes or other means for discharging the water from the chamber k downwardly into the urinal chamber and in all directions against the walls of the latter. m is any suitable means for introducing water into the chamber k .

The wall d bulges outwardly at the bottom, as indicated at n , the width of the thus-formed forwardly projecting part of the urinal-chamber-forming portion of the structure being such that a person using the urinal may stand with said part more or less under him and his feet both sides of it. From its lower end upwardly said wall, viewed in front elevation, tapers gradually, as shown in Fig. 1. The major part of the urinal chamber from its intake (outlet l for the water supply chamber k) downwardly gradually tapers upwardly, this being because both walls $a a$ are vertical and the

major upper part of wall *d* slopes rearwardly gradually. The flushing water being discharged from the intake *l* in all directions against the sides of the urinal 5 chamber, there is therefore a uniform flow of water over the whole inside surface of the urinal chamber downwardly to an extent including especially, and at least, the part of said chamber which is subjected to 10 direct urinal service; in short, the formation of the urinal chamber is such as to encourage a surface-flow rather than a drip or free falling of the flushing water and a surface-flow that is uniformly distributed 15 over the whole interior face of the urinal chamber and especially that part thereof which is most frequently and directly wetted by urine. This advantage is accomplished, it will be observed, by use of a 20 localized or single intake.

Wall *d* is formed with a vertically elongated opening *o* extending from a point near the top of the wall *d* well to the front of the bulging portion *n* of said wall, but sufficiently above the bottom wall *b* to leave the lower front part of wall *d* intact excepting (in the preferred form) for a vertical slit *p* which extends from said wall *b* upwardly, merging into the opening *o*. Below the opening, therefore, the wall *d* serves 25 as a guard or fender to prevent drippings of urine from spattering from the wall *b* outside of the urinal chamber; the disposition of the lower end of said opening is such 30 that it is well under the user, so that such drippings fall within the chamber and not on exterior surfaces. It will be observed that the angular disposition of the walls *a a* makes the interior back surface of the urinal 35 chamber concave, as at *a'*, and that the aperture *o* is relatively narrow with respect to the inside width of the urinal chamber, thus the spattering action of the urine against the back wall of the structure is minimized 40 and in any event is confined wholly within the urinal chamber. The slit *p* is useful to permit drainings from the floor, when the same is mopped or washed, to find their way 45 into the urinal. To confine the flushing water within the urinal chamber wall *d* may be provided with an interior flange *q* extending substantially all around the opening *o* at the edge thereof.

The flushing water enters the outlet *g* 50 more or less from all sides thereof, and if desired an auxiliary stream of clean water may be supplied from the chamber *k* to the said outlet by the duct *s* formed in the back of the urinal structure. I find it desirable, 55 however, as more effectively flushing the outlet to have the back surface-portion *r* of the chamber *e*, which surface-portion stands vertically directly over the outlet, so that there will be a drain of water directly

into said outlet as well as the surface-flow 65 thereinto.

In the back of the urinal structure may be formed a vertical duct *t* for carrying off odors and gases arising from the outlet, the same reaching from basin *f* upwardly to 70 any suitable pipe leading out of doors.

It will be understood that the walls *a a* are disposed in angular relation to each other so as to afford wings imparting privacy to the urinal proper. Regardless, however, of the relation and function of the walls it will be apparent that the entire structure is materially strengthened by the existence therein, as a brace between said walls, of the wall *d* forming a urinal chamber 80 therein, so that the structure is capable of being handled, before it reaches the kiln, with less likelihood of becoming distorted and of undergoing the baking process with less susceptibility to warping influences. 85

I do not wish to be limited to the precise construction herein shown and described, what I claim being,

1. A urinal having a urinal chamber provided with a front wall and a bottom, said 90 wall having a vertically elongated opening of limited width relatively to the inside width of the urinal chamber and extending downwardly in said wall short of said bottom and also having a narrow vertical slit 95 extending from said opening downwardly to said bottom.

2. A urinal formed of ceramic material and consisting of two upright walls joined with each other and arranged angularly 100 and a vertically elongated apertured front wall arranged in the angle between and joined from top to bottom at its lateral portions with said first-named walls and forming with the parts of the latter relatively 105 back of it the urinal chamber, the remaining parts of said first-named walls forming forwardly projecting wings.

3. A urinal formed of ceramic material and consisting of two upright walls joined 110 with each other and arranged angularly and a vertically elongated apertured front wall having an upwardly tapering form in front elevation and arranged in the angle between and joined from top to bottom at its 115 lateral portions with said first-named walls and forming with the parts of the latter relatively back of it the urinal chamber, the remaining parts of said first-named walls forming projecting wings.

4. A urinal formed of ceramic material and consisting of two upright walls joined with each other and arranged angularly, a vertically elongated apertured front wall arranged in the angle between and joined 120 from top to bottom at its lateral portions with said first-named walls and forming with the parts of the latter relatively back

of it the urinal chamber, the remaining parts of said first-named walls forming projecting wings, and a hollow ledge projecting forwardly from said first-named walls over the front wall and having a restricted outlet discharging from its interior downwardly into said urinal chamber.

In testimony whereof I affix my signature in the presence of witnesses.

STEPHEN D. BAKER.
